CLAIM

We claim the ornamental design for a tool head interface for connection to tool body, as shown and described in the figures.

DESCRIPTION

FIG. 1 is a perspective view of a tool head interface embodying the invention.

FIG. 2 is a left side view of the tool head interface shown in FIG. 1.

FIG. 3 is a right side view of the tool head interface shown in FIG. 1.

FIG. 4 is a front view of the tool head interface shown in FIG. 1.

FIG. 5 is a rear view of the tool head interface shown in FIG. 1.

FIG. 6 is a top view of the tool head interface shown in FIG. 1.

FIG. 7 is a bottom view of the tool head interface shown in FIG. 1.

FIG. 8 is a perspective view of another embodiment of a tool head interface.

FIG. 9 is a left side view of the tool head interface shown in FIG. 8.

FIG. 10 is a right side view of the tool head interface shown in FIG. 8.

FIG. 11 is a front view of the tool head interface shown in FIG. 8.

FIG. 12 is a rear view of the tool head interface shown in FIG. 8.

FIG. 13 is a top view of the tool head interface shown in FIG. 8.

FIG. 14 is a bottom view of the tool head interface shown in FIG. 8.

FIG. 15 is a perspective view of another embodiment of a tool head interface.

FIG. 16 is a left side view of the tool head interface shown in FIG. 15.

FIG. 17 is a right side view of the tool head interface shown in FIG. 15.

FIG. 18 is a front view of the tool head interface shown in FIG. 15.

FIG. 19 is a rear view of the tool head interface shown in FIG. 15.

FIG. 20 is a top view of the tool head interface shown in FIG. 15.

FIG. 21 is a bottom view of the tool head interface shown in FIG. 15.

FIG. 22 is a perspective view of another embodiment of a tool head interface.

FIG. 23 is a left side view of the tool head interface shown in FIG. 22.

FIG. 24 is a right side view of the tool head interface shown in FIG. 22.

FIG. 25 is a front view of the tool head interface shown in FIG. 22.

FIG. 26 is a rear view of the tool head interface shown in FIG. 22.

FIG. 27 is a top view of the tool head interface shown in FIG. 22; and,

FIG. 28 is a bottom view of the tool head interface shown in FIG. 22.

The portions of the tool head interfaces shown in broken lines are included for the purpose of illustrating environment and form no part of the claimed design.
